UNITED STATES PATENT OFFICE

171,590

FOOTBALL TRAINING BLOCKING PAD OR SIMILAR ARTICLE

Martin John Gilman, Gilman, Conn.

Application September 15, 1953, Serial No. 26,808

Term of patent 14 years

(Cl. D34—5)

To all whom it may concern:

Be it known that I, Martin John Gilman, a citizen of the United States and a resident of Gilman, Connecticut, have invented a new, original, and ornamental Design for a Football Training Blocking Pad or Similar Article, of which the following is a specification, reference being had to the accompanying drawing, forming a part hereof, in which

I claim:

The ornamental design for a football training blocking pad or similar article, as shown.

MARTIN JOHN GILMAN.
